UNITED STATES PATENT OFFICE

103,953

DESIGN FOR A DECORATIVE LIGHT

Leopold Pollock, New York, N. Y.

Application January 16, 1937, Serial No. 67,081

Term of patent 7 years

To all whom it may concern:

Be it known that Leopold Pollock, a citizen of the United States, residing in New York city, in the county and State of New York, has invented a new, original, and ornamental Design for a Decorative Light, of which the following is a specification, reference being had to the accompanying drawing, forming a part thereof.

Fig. 1 is a top plan view of the decorative light; and

Fig. 2 is a front elevational view thereof.

I claim:

The ornamental design for a decorative light, as shown.

LEOPOLD POLLOCK.
